(57) CLAIM

I claim the ornamental design for a paint brush for use in corner applications, as shown and described.

DESCRIPTION

FIG. 1 is a perspective view of one embodiment of a paint brush according to the present invention;

FIG. 2 is a view as seen from the end of the handle shown in FIG. 1;

FIG. 3 is a view as seen from the end of the brush head shown in FIG. 1;

FIG. 4 is a front view of the paint brush shown in FIG. 1; FIG. 5 is a rear view of the paint brush shown in FIG. 1; FIG. 6 is a left side view of the paint brush shown in FIG. 1; and,

FIG. 7 is a right side view of the paint brush shown in FIG. 1.

Features shown in broken lines in the drawings are not part of the claim.
